US0D1078618S

(12) **United States Design Patent** (10) Patent No.: **US D1,078,618 S**
(45) Date of Patent: ** Jun. 10, 2025

(54) **CHARGER**

(71) Applicant: **Polar Electro Oy**, Kempele (FI)

(72) Inventors: **Olli Komulainen**, Kempele (FI); **Lauri Lumme**, Kempele (FI)

(73) Assignee: **Polar Electro Oy**, Kempele (FI)

(**) Term: **15 Years**

(21) Appl. No.: **29/854,605**

(22) Filed: **Sep. 27, 2022**

(30) **Foreign Application Priority Data**

Jul. 13, 2022 (EM) 009086374-0001
